UNITED STATES PATENT OFFICE.

HENRY GASTON EPPS, OF WACO, TEXAS.

COAL-OIL GENERATOR.

1,346,370.

Specification of Letters Patent. Patented July 13, 1920.

Application filed September 9, 1919. Serial No. 322,616.

To all whom it may concern:

Be it known that I, HENRY GASTON EPPS, a citizen of the United States, residing at Waco, in the county of McLennan and State 5 of Texas, have invented a new and useful Coal-Oil Generator, of which the following is a specification.

This invention relates to improvements in oil burners, and more particularly to oil 10 burners of the overlying retort type.

The primary object of the invention is to provide a burner having means to permit the same to be positioned within the fire box of a stove, by means of the especially 15 constructed support.

A further object of the invention is to construct a supporting means as described, which will provide means for efficiently supporting the burner on the bottom of the 20 fire box of a coal, or wood stove, in the event that the burner is to be used for converting a coal or wood stove, into a temporary oil stove.

A further object of the invention is to provide means for effectively directing a quantity of air to the burners, to materially aid 25 in the combustion of the oil passing through the burners.

With the foregoing and other objects in 30 view which will appear as the description proceeds, the invention resides in the combination and arrangement of parts and in the details of construction hereinafter described and claimed, it being understood that 35 changes in the precise embodiment of the invention herein disclosed, may be made within the scope of what is claimed without departing from the spirit of the invention.

Referring to the drawing:—

40 Figure 1 illustrates a side elevational view, partly in section, of a burner constructed in accordance with the present invention.

Fig. 2 is a top plan view of the same, and Fig. 3 is a transverse sectional view taken 45 on line 3—3 of Fig. 1.

Referring to the drawing in detail, the reference character 5 indicates the base or direct supporting element for the burner proper, and includes a rectangular plate, 50 formed of any suitable material, but preferably cast iron.

This base 5, is provided with a central rectangular depression 6, providing a receptacle or pan for aiding in pre-heating the 55 burner, the pan being large enough to receive

a quantity of fuel sufficient to pre-heat one of the pipes of the burner, which is supported over the pan, for converting the initial charge of oil passing through the pipe, into a vapor to be readily ignited. 60

Adjacent each end of the depressed portion 6, is an opening 7, said openings being provided with upwardly extending walls, terminating at a point a short distance above the base, the opposed walls 8 and 9, being 65 provided with a centrally disposed cut-out portion 10, the same being curved to conform to the curvature of one of the pipes of the burner, for supporting the same in proper relation to the walls of the openings, 70 to insure proper combustion of the fuel passing through the burner.

The integral flange 11 depends from the base 5, and forms the front supporting wall of the base 5, the same having connection 75 with the end flanges 12 and 13, also formed integral with the base 5, to house a volume of air under the base 5, whereupon the same is directed upwardly through the openings 7 of the base. 80

A rear wall 14, is also formed integral with the base 5, and extends upwardly therefrom, the same having connection with the end walls 15 and 16, which extend forwardly from the rear wall 14, the front edges of 85 said end walls terminating at points substantially the width of the base or support 5, to provide a clearance for the pipes of the burner, to be hereinafter more fully described, so that the same may be supported 90 in proper relation over the depressed portion 6, and openings 7 of the base.

The burner proper, includes the horizontally disposed pipe 17, which has connection with an oil supply tank, not shown, the passage of oil into said pipe 17 being controlled by the valve member 18. One end of the pipe 17 is disposed in parallel relation therewith, to form a section 18', the two sections of the pipe being connected by the curved portion 19, whereby the fuel passing through the portion 17, is directed to the section 18', which forms the burner pipe. 100

This burner pipe 18', is supported in the cut-out portions 10, of the walls 8 and 9, 105 and held therein against displacement by means of the cleats 20, which are curved to embrace portions of the pipe 18, the ends 21 thereof being apertured to receive the bolts 22. 110

- In the upper surface of the pipe 18, and disposed at points substantially centrally of the openings 7, are the openings 23, which constitute the burners of the device. Supported above each of the openings 23, is a flame deflector 24, each of which being provided with a circular supporting portion 25, which embraces the pipe 17, for supporting the deflector plate 24, the same being circular in formation and of a diameter to spread the flame issuing from the burner openings 23, to cause the same to envelop the portion of the pipe 17, supported above the burner openings 23.
- 15 In order that the pipe 17, may be supported in proper relation to permit the flame issuing from the burner openings 23, to contact with the same, the horizontal supporting arm 26 is provided, one end 20 thereof being threaded as at 27, and passes through an opening formed in the rear wall 14; the threaded portion 27 adapted to accommodate the clamping nuts 28, engaging opposite sides of the wall 14, for clamping the wall 14 therebetween.
- 25 The opposite end of the supporting arm 26 is formed into an eye 29, which eye embraces the pipe 17, for securing the pipe 17 with relation to the wall 14.
- 30 In operation, a quantity of fuel is placed in the depressed portion 6, the valve 18, is now turned to permit oil or other liquid fuel to pass through the pipe 17, and into the portion 18' thereof, whereupon the fuel 35 within the depressed portion or tray 6, is ignited with the result that the fuel within the section 18' of the pipe is vaporized.

This vapor issues from the burner openings 23, and is ignited. The flames from the burner openings 23 are directed upwardly 40 and engage the deflector plates, which retain the heat, causing the fuel passing through pipe 17 to be vaporized thereby.

Having thus described the invention, what is claimed is:—

45 In a burner, a base, flanges depending from the base to provide supports for the base, one of said flanges being cut away to provide an air passageway, said base being provided with an opening adjacent each end thereof, and having a depressed portion providing a receptacle, the depressed portion being substantially long, the ends thereof terminating at points adjacent the openings, a rear wall formed integral with the 50 base, said rear wall having integral end walls, a supporting arm having an eye formed at one end thereof, means for securing the opposite end of the supporting arm to the rear wall, a pipe extending 55 through the eye of the supporting arm, means for securing a portion of the pipe to the base, and said pipe having burner openings.

60 In testimony that I claim the foregoing as my own, I have hereto affixed my signature in the presence of two witnesses.

HENRY GASTON EPPS.
